UNITED STATES PATENT OFFICE.

EDWIN M. WINTER, OF BROOKLYN, NEW YORK.

PROCESS AND APPARATUS FOR FORMING HOLLOW CASTINGS.

1,362,978.

Specification of Letters Patent. Patented Dec. 21, 1920.

Application filed September 4, 1919. Serial No. 321,523.

To all whom it may concern:

Be it known that I, EDWIN M. WINTER, a citizen of the United States, residing in borough of Brooklyn, in the county of 5 Kings and State of New York, have invented certain new and useful Improvements in Processes and Apparatus for Forming Hollow Castings, of which the following is a specification.

10 My process and apparatus for forming hollow castings relates to a process or method which consists in compressing the metal or other material to fill the die and withdrawing superfluous material or metal 15 from the die to form the casting from the residue in the die, and the apparatus by which this process or method is accomplished.

A principal feature of my process or 20 method consists in forcing material, or metal in molten or suitable form, into a die by compression of the material or metal, and withdrawing superfluous material or metal from the die by suction to form the casting 25 from the residue in the die, said suction being consequent from the compression which forced the material or metal into the die.

A further feature of my process or method consists in restricting or controlling to a 30 predetermined degree the flow of material or metal when forced into the die by compression, and in restricting or controlling to a predetermined degree the withdrawal of the 35 superfluous material or metal from the die by suction consequent from said compression.

In my process or method I employ a novel and peculiar apparatus, a preferred embodiment of which is illustrated in the accompanying drawings.

40 Figure 1, is a top or plan view of such apparatus.

Fig. 2, is a side elevation of such apparatus, partly in central vertical longitudinal section.

45 Fig. 3, is a view of such apparatus on the line 3—3 of Fig. 2, looking in the direction of the arrows.

Similar letters or numerals refer to similar parts throughout the several views.

50 Reference being had to the foregoing drawings, the said apparatus comprises the container or pot A, which may be made of any suitable metal or material, capable when desirable of withstanding heat or flame applied thereto. The container or pot A is intended to be filled to a desired normal sur-

face level, such as a, with suitable material or metal in molten or such other form as may be required.

The cylinder C is supported in the receptacle or pot A by the bracket 10, or other suitable means, the bracket 10, or other suitable means, being arranged to prevent leakage at the points of connection.

The port or aperture 11, affords a means 65 for communication between the container or pot A and the cylinder C, the port or aperture 11 being placed slightly below the normal surface level, such as a, of the mold material or metal in the container or pot A. 70

The piston or plunger P is provided for the cylinder C, and arranged to afford compression within the cylinder C.

The lever arm L is pivotally secured to the outer side of the casing of the container or 75 pot A in any suitable manner, and is operatively attached, as at b, Fig. 2, about midway of its length, to the piston or plunger P.

The conduit or duct D is attached at one end to the bottom of the cylinder C, and is 80 received at its other end in the bracket 12 which has a bore 13, the bracket 12 being secured to the inner side of the casing of the container or pot A by bolts or other suitable means. The nozzle N having a bore 14, 85 which is continuous of the bore 13 of the bracket 12, is seated at 15 in the bracket 12 by threaded or other suitable means which provides for prevention of leakage at the points of connection. The nozzle N has an 90 enlargement 16 near its upper end, the upper end 17 of the nozzle N being diminished to substantially the diameter and bore of the lower end 15 of the nozzle. The end 17 of the nozzle N extends through the casing of 95 the container or pot A, and in such suitable manner as to prevent leakage from the container or pot A. The bushing B is received in the casing of the container or pot A adjacent to the lower end of the bore 13 of the bracket 12, being secured to the casing and to the bracket 12, by threaded or other suitable means and packed or otherwise suitably arranged to prevent leakage at the points of connection.

The bushing B is bored to form 100 a perforation to receive in a liquid-tight manner and frictionally hold a restricting or controlling rod R, having a nose 18, which nose is locatable in the enlargement 16 of the nozzle N, and adapted for upward 110 or downward movement by movement of the rod R by means of a handle H or other suit-

able manipulating means which is arranged outside the casing of the container or pot A, or outside of a heat chamber such as J, when the apparatus is provided with such a heat chamber.

5 A heat chamber J may be provided outside of the casing of the container or pot A, and suitably arranged as to draft, and with flame jets such as 19.

10 The die carrier S is supported on the top of the container or pot A by a seat 20, which engages the end 17 of the nozzle N, and carries a mold or die 21 in such position that the filler end thereof is in operative communication with the bore of the upper end 17 of the nozzle N when the die carrier S is removably secured or latched to the container or pot A by the latch ends 22, which engage the bar 23 on the casing of the container or pot A. The die carrier S is divided or split as at 24, Fig. 2, to permit opening of the die carrier to place a die therein or remove a die therefrom, the die also being divided or split to permit opening thereof 25 to uncover the mold formed therein. The die carrier S is retained in closed position by latches 25, or other suitable means, and is provided with an arm 26, for lifting or removing the die carrier.

30 My process or method is carried into operation as follows:

The container or pot A is filled with the requisite material or metal to a desired surface level such as a, the piston or plunger P being in upward position, the bottom thereof being above the port or aperture 11 and substantially on a line with the normal surface lever a, of the material or metal. The material or metal passing through the port 35 or aperture 11 enters the cylinder C and is thence conveyed by the conduit or duct D to the nozzle N, the material or metal having the same surface level in the container or pot A, conduit or duct D, and nozzle N. 40 The die carrier S with a die 21, being in such position that the filler end of the die is in direct communication with the bore of the extended end 17 of the nozzle N, downward movement of the piston or plunger P closes the port or aperture 11 and 45 compresses the material or metal in the cylinder C, conduit or duct D, and nozzle N, and forces the material or metal into the die 21.

50 Upward movement of the piston or plunger P, after the prior downward movement thereof, withdraws material or metal from the interior of the die 21, leaving in the die that part of the material next to the surface thereof which cooled and hardened first, thus forming a hollow casting. Adjusting movement of the restricting or controlling rod R locates the nose 18 at different distances from the upper line of the enlargement 16; and the nose 18 so restricts or

controls the withdrawal of the mold material or metal from the die 21 by suction, that considerable variations of force exerted upon the plunger P, above a normal amount, have practically no tendency to hasten or retard the withdrawal of the material. The nose 18 is set at the location that gives the best speed for the kind of material or metal used and the form or class of casting desired, after which little attention need be given to the amount of force used by the operator for operating the plunger P.

While I have described and shown a single assembly of plunger and parts coacting therewith, it is obvious that the container or pot A can be extended or otherwise arranged to provide for any desired number of assemblies of plungers and coacting parts, so that any desired number of castings can be formed at the same time by the process 85 and apparatus.

I claim:

1. A process for forming castings comprising introducing material into a die; withdrawing a part of the material from the die; and restricting the introduction and withdrawal of the material in proportion to the material used.

2. A process for forming castings comprising introducing material into a die; withdrawing a part of the material from the die before the interior thereof has hardened; and automatically and adjustably restricting by constriction the introduction and withdrawal of the material in proportion to the volume of material used for rendering the speed of such withdrawal and introduction practically independent of the force exerted in effecting them.

3. A process for forming castings consisting in introducing material into a die; withdrawing a part of the material from the die, a portion being permitted to harden therein; restricting the withdrawal of the material for rendering the speed of such withdrawal practically independent of the force causing such withdrawal; said restricting automatically holding the material in the die long enough for the outer part of the casting to harden but permitting the withdrawal a part of the material from the die before the interior thereof has hardened so that a hollow casting is left in the die.

4. A process for forming castings consisting in forcing mobile material into a die; adjustably and automatically restricting by constriction the introduction of the material in proportion to the volume of material used for rendering the speed of such introduction practically independent of the force exerted in said forcing; withdrawing a part of the material from the die by suction before the interior thereof has hardened so that a hollow casting is left in the die.

- die; and adjustably and automatically restricting by constriction the withdrawal of the material, in proportion to the volume of material used, for rendering the speed of such withdrawal practically independent of the force exerted in said suction; said restricting automatically holding the material in the die long enough for the outer part of the casting to harden but permitting the 10 withdrawing a part of the material from the die before the interior thereof has hardened so that a hollow casting is left in the die.
5. In combination, means for forcing into a die mobile material for forming a casting and holding the material in the die long enough for the outer part of the casting to harden and withdrawing the material from the die before the interior thereof has hardened so that a hollow casting is left in the die; and adjustable restricting means 20 restricting by constriction the introduction and withdrawal of the material from the die for rendering the speed of such withdrawal or introduction practically independent of the force exerted in said forcing and suction.
6. In combination, a die; a nozzle having, one end communicating with said die, and an intermediate enlargement; a nose in said enlargement adapted to be adjustably held disposed different distances from the center thereof; and means for forcing material into said nozzle.
7. In combination, a die; a nozzle having a closed end, an end communicating with said die, and an intermediate enlargement; a rod passing in a liquid-tight manner into said nozzle and adjustably held therein, and provided with a nose in said enlargement 30 adapted to be disposed different distances from the center thereof; and means for introducing material into said nozzle between said nose and said closed end.
8. In combination, a container; a die; a nozzle having one end closed and the other communicating with said die, the intermediate part of the nozzle being provided with an enlargement; a rod passing in a liquid-tight manner through said closed end and adjustably held therein, and provided at its inner end with a nose adapted to be disposed different distances from the center of said enlargement; a handle on the outer end of the rod exterior to the container; means in said 40 container for forcing material into the nozzle between said nose and the closed end.
9. In combination, a container for mobile material provided with an opening therein; a bracket fixed over said opening and provided with a bore; a die; a nozzle having one end communicating with the inner end of said bore and the other end communicating with said die; the intermediate part of the nozzle being provided with an enlargement; a bushing in the outer end of said bore and
5. In combination, means for forcing into a die mobile material for forming a casting and holding the material in the die long enough for the outer part of the casting to harden and withdrawing the material from the die before the interior thereof has hardened so that a hollow casting is left in the die; and adjustable restricting means 10 restricting by constriction the introduction and withdrawal of the material from the die for rendering the speed of such withdrawal or introduction practically independent of the force exerted in said forcing and suction.
6. In combination, a die; a nozzle having, one end communicating with said die, and an intermediate enlargement; a nose in said enlargement adapted to be adjustably held disposed different distances from the center thereof; and means for forcing material into said nozzle.
7. In combination, a die; a nozzle having a closed end, an end communicating with said die, and an intermediate enlargement; a rod passing in a liquid-tight manner into said nozzle and adjustably held therein, and provided with a nose in said enlargement 20 adapted to be disposed different distances from the center thereof; and means for introducing material into said nozzle between said nose and said closed end.
8. In combination, a container; a die; a nozzle having one end closed and the other communicating with said die, the intermediate part of the nozzle being provided with an enlargement; a rod passing in a liquid-tight manner through said closed end and adjustably held therein, and provided at its inner end with a nose adapted to be disposed different distances from the center of said enlargement; a handle on the outer end of the rod exterior to the container; means in said container for forcing material into the nozzle between said nose and the closed end.
9. In combination, a container for mobile material provided with an opening therein; a bracket fixed over said opening and provided with a bore; a die; a nozzle having one end communicating with the inner end of said bore and the other end communicating with said die; the intermediate part of the nozzle being provided with an enlargement; a bushing in the outer end of said bore and
10. In combination, a container for mobile material and provided with an opening in the lower part thereof; a bracket fixed over said opening and provided with a bore; a die; a nozzle having one end communicating with the inner end of said bore and the other end communicating with said die; the intermediate part of the nozzle being provided with an enlargement having over twice the diameter of the nozzle; a bushing in the outer end of said bore and said opening and provided with a perforation coaxial with the nozzle; a rod passing in a liquid-tight manner through said perforation and slidably frictionally adjustably held therein, and provided at its inner end with a nose adapted to be disposed different distances from the center of said enlargement and having a diameter nearly as great as the interior diameter of the nozzle; a handle on the outer end of the rod; a cylinder in said container and having an aperture communicating with said material; a plunger in the cylinder; means for operating the plunger; and means for establishing communication between the cylinder and an intermediate part of said bore.
11. In combination, means for introducing material into a mold by pressure, and withdrawing part thereof from the mold by suction, and means movable parallel to the line of flow in said means for introducing for restricting such introduction.
12. In combination, means for introducing material into a mold by pressure, and withdrawing part thereof from the mold by suction, and means movable parallel to the line of flow in said means for introducing for restricting such withdrawal.
13. In combination, means for introducing material into a mold and withdrawing part of it from the mold, and adjustable restricting means restricting such introduction and withdrawal.
14. In combination, means for forcing material into a mold and withdrawing a part of it from the mold before the interior thereof has hardened so that a hollow casting is left in the mold; and adjustable restricting means restricting the introduction of the material into the mold.
15. In combination, man-operated means for forcing material into a mold and with-

drawing a part of it from the mold before the interior thereof has hardened so that a hollow casting is left in the mold; and adjustable restricting means restricting the withdrawal of the material from the mold.

16. In combination, a mold; a nozzle communicating with said mold; means for introducing casting material into said nozzle; and means in the nozzle for restricting the flow of said material therethrough; said nozzle having an enlarged portion provided with constricted ends, and said last mentioned means being movable in said enlargement to position for coöperating with said constricted ends for restricting the flow of said material through the nozzle.

17. In combination, a mold; a nozzle communicating with said mold; means for introducing casting material into said nozzle; and adjustable means in the nozzle for restricting the flow of said material therethrough; said nozzle having an enlarged portion provided with constricted ends, and said last mentioned means being movable in said enlargement to position for coöperating with said constricted ends for restricting the flow of said material through the nozzle.

18. In combination, a mold; a nozzle communicating with said mold; means for introducing material into said nozzle; and means within the nozzle and spaced from the walls thereof for restricting the flow of material therethrough.

19. In combination, a mold; a nozzle communicating with said mold; means for introducing casting material into said nozzle and mold, and withdrawing casting material from said mold and nozzle; and means in the nozzle for restricting passage of casting material therethrough; said nozzle having an enlarged portion forming a chamber with constricted ends and said last mentioned means being locatable in said chamber for coöperating with said constricted ends for restricting the flow of casting material through said nozzle.

20. In combination, a mold; a nozzle communicating with said mold; means for forcing by pressure casting material into said nozzle and mold, and withdrawing casting material from said mold and nozzle by suction; and means in the nozzle for restricting the passage of casting material therethrough; said nozzle having an enlarged portion forming a chamber with constricted ends, and said last mentioned means being located in said chamber for coöperating with said constricted ends for restricting the flow of casting material through said nozzle when said flow is caused either by pressure or by suction.

EDWIN M. WINTER.
